CLAIM

The ornamental design for a lateral hook merchandising bar and display strip, as shown and described.

DESCRIPTION

FIG. 1 is a front, right perspective view of the lateral hook merchandising bar and display strip showing my new design with the lateral hook merchandising bar detached from the display strip;

FIG. 2 is a front, right perspective view of the lateral hook merchandising bar and display strip of FIG. 1 with the lateral hook merchandising bar attached to the display strip;

FIG. 3 a bottom plan view of FIG. 2;

FIG. 4 is a top plan view thereof; and,

FIG. 5 is a rear, right perspective view thereof.

The back views are substantially flat and unornamented.
